UNITED STATES PATENT OFFICE.

LEO B. WARD, OF SAN FRANCISCO, CALIFORNIA.

SANITARY TOILET-SEAT.

1,248,216.

Specification of Letters Patent.

Patented Nov. 27, 1917.

Application filed December 29, 1916. Serial No. 139,654.

To all whom it may concern:

Be it known that I, LEO B. WARD, a citizen of the United States, residing at San Francisco, in the county of San Francisco and State of California, have invented new and useful Improvements in Sanitary Toilet- Seats, of which the following is a specification.

This invention relates to sanitary attachments for use in connection with toilet seats.

The object of the invention is to provide a device of this character, whereby each user of the toilet may be provided with an individual cover for the seat, to prevent possible communication of disease.

Another object of the invention is to produce a device of this character which is simple and economical in construction, and one that is at all times ready for instant use.

With the above objects in view the invention consists of the following novel combination and arrangement of parts as set forth in the following description and illustrated in the accompanying drawings, in which;

Figure 1 is a plan view of the device attached to the seat of a toilet;

Fig. 2 is a front elevation of the same;

Fig. 3 is an enlarged cross sectional view of the device;

Fig. 4 is an enlarged longitudinal sectional view;

Fig. 5 is a detailed perspective view of the tensioning spring.

Referring to the drawings wherein like characters of reference denote corresponding parts, the bowl of the toilet is shown at 1, the seat at 2. The container which is of cylindrical form, and within which is mounted a continuous roll of preferably antiseptic paper, is shown at 3 and is attached to the seat by means of a pair of brackets 4. These brackets are preferably secured in the underside of the edge of the seat as shown so that the paper 5 may be conveniently fed along the upper surface of the seat in position for use. The container 3 is provided at each of its ends with grooves 6 extending to the center of the cylinder, to provide bearings for the rod 7 upon which the roll of paper is mounted. This roll is preferably provided with a pasteboard tube 8 adapted to snugly fit the rod 7 so that a new roll may be easily slid into position.

The rod 7 is provided near one of its ends with a metal disk 9 fast on the shaft, and at its opposite end with a removable, prefer-

ably rubber, disk 10, which may be so adjusted upon the shaft as to properly position the roll with respect to the paper guide to be presently described.

The paper guide 11 is mounted upon the outside of the container 3, and comprises end sections 12 by means of which it is secured to the container, and a horizontal top portion 13. Secured at one end of this top portion is a tension spring 14, of approximately the same length as the paper guide, and is adapted to contact along its free edge with the underside of the guide in order to properly tension the paper as it is drawn from the roll. Suitable openings 16 are provided at the top of this guide for the purpose of permitting access to the paper should it be necessary at any time to push the paper through by hand. The paper 5 is formed with a series of openings 17 having slits 18 radiating therefrom, and in order to prevent the paper from becoming crumpled or stuck owing to its contact with the edge of the tension spring 14, the said spring is provided with an offset central portion 19 to prevent contact with the paper except along the edges thereof, leaving that portion of the paper containing the opening 17 and slits 18 to pass beneath the spring without engagement.

The above stated guide 11 is positioned upon the outside of the container 3, and in order to permit of the paper passing through this guide the said container is provided with a longitudinal slot 20 upon its periphery in adjusted position to the entrance to the said guide.

From the foregoing description when taken in connection with the accompanying drawings, it will be seen that the invention provides a neat, compact and simple device for supplying an individual sanitary covering to a toilet seat, in order to prevent communication of diseases where the said seat is used by a number of persons.

Having described the invention, what is claimed is:

1. A toilet paper container comprising a slotted paper receiving receptacle, means for mounting a roll of paper to revolve therein, a guide mounted upon the outside of said receptacle, said guide comprising spaced parallel walls defining a passage open at each end, one end of said passage being located adjacent the slot in the receptacle, and a tensioning spring located within said pas-

sage in a manner to engage the side edges of the paper only for the purpose of tensioning the same.

2. A toilet paper container comprising a slotted paper receiving receptacle, means for mounting a roll of paper to revolve therein, a guide mounted upon the outside of said receptacle, said guide comprising spaced parallel walls defining a passage open at each end, one end of said passage being located adjacent the slot in the receptacle, and a tensioning spring located within said passage in the path of the paper, said spring being provided with a central offset portion spaced from the paper and end paper engaging portions, whereby the said paper

may be tensioned by contact along its edges only.

3. The combination with a receptacle having a slot therein, of a shaft mounted to revolve within said receptacle and adapted to receive a roll of paper, a stop permanently secured upon said shaft for engagement with one end of said roll and a flexible stop adapted to be removably positioned upon said shaft at the opposite end of said roll, for frictional engagement with the shaft, whereby rolls of various widths may be positioned upon the shaft.

In testimony whereof I affix my signature.

LEO B. WARD.
